(57) **CLAIM**

The ornamental design for a vehicle accessory, as shown and described.

DESCRIPTION

FIG. 1 is a bottom front side perspective view of a vehicle accessory showing my new design;

FIG. 2 is a top front side perspective view thereof;

FIG. 3 is a top plan view thereof;

FIG. 4 is a bottom plan view thereof;

FIG. 5 is a left side view thereof;

FIG. 6 is a front elevation view thereof;

FIG. 7 is a back elevation view thereof; and,

FIG. 8 is a top front side perspective view thereof, shown with the adhesive surface partially removed and cut away. Right side views not shown are mirror images of left side views. Any broken lines illustrative of environmental structure in the drawings are not part of the design sought to be patented.

1 Claim, 8 Drawing Sheets
